UNITED STATES PATENT OFFICE.

ELISE BIGALKE, OF NEW YORK, N. Y.

DESIGN FOR A COMBINATION DISH.

Application filed December 13, 1924. Serial No. 11,697. Term of patent 3½ years.

To all whom it may concern:

Be it known that I, ELISE BIGALKE, a citizen of Germany, residing at New York, in the county of New York and State of New York, have invented a new, original, and ornamental Design for a Combination Dish, of which the following is a specification, reference being had to the accompanying drawing, forming a part thereof.

Fig. 1 is a plan view, and Fig. 2 an elevational view of my combination dish, showing my design.

I claim:

The ornamental design for a combination dish, as shown.

ELISE BIGALKE.
